Ernest Albert Parker, St. Ninians, Brundall, Norfolk, England

Application July 24, 1936, Serial No. 92,440
In Great Britain May 5, 1936

1 Claim. (Cl. 36—43)

This invention relates to an improved method of manufacture of boots and shoes whereby the toe portions and ball portions thereof can be made without metal tacks, nails or wire staples so that there is no danger of metal working into the interior of the shoe so as to be liable to injure the foot. By means of the improved method of manufacture the use of separate bottom filling materials is unnecessary thus avoiding the necessity of using additional materials as usually employed for this purpose whilst at the same time obtaining increased flexibility and comfort.

According to the present invention an insole for use in the manufacture of boots and shoes is marginally reduced in thickness on its lower surface, to form the equivalent to bottom filling materials, by skiving or splitting the underside edge margin of the toe portion of the insole. The skiving or splitting preferably extends over the ball portion of the insole up to approximately the shank and heel portion. The toe portion and shank and heel portion of the insole are preferably divided, whilst sheeting of vulcanite, vulcanized board or similar material is inserted between the separate layers so as to form a three-ply toe portion and shank and heel portion, these portions being connected together by a solid ball portion.

According to another aspect of the invention an insole for use in the manufacture of boots and shoes consists of a three-ply toe portion and shank and heel portion interconnected by a solid ball portion, the thickness of the toe portion, and preferably also of the ball portion being marginally reduced to leave a projecting portion which constitutes an equivalent to the usual bottom filling materials.

The invention will now be described with reference to the accompanying drawings, wherein

Fig. 1 is a perspective view of a piece of leather shaped in the form of an insole.

Fig. 2 is a perspective view of an insole of which the toe portion and the shank and heel portion have been divided.

Fig. 3 is a similar view to Fig. 2 wherein sheeting has been inserted in the divided toe portion and shank and heel portion.

Fig. 4 is a perspective view of a composite insole.

Fig. 5 is a perspective view of a composite insole with the marginal edge skived or split at the toe portion.

Fig. 6 is a perspective view of an insole of which the marginal edge has been skived or split along the toe portion and ball portion, the skived

margin having applied thereto an adhesive coating or a fabric coated on both sides with adhesive, the outer layer of adhesive being covered by a protecting covering.

Fig. 7 is a similar view to Fig. 6 in which the 5 insole is provided with a metal shank stiffener.

Fig. 8 is a perspective view of the insole mounted on a last and having the upper partly secured thereto.

Fig. 9 is a view similar to Fig. 8 with the upper 10 almost completely lasted to the insole, and

Fig. 10 is a cross-sectional view of an upper lasted to an insole.

Referring now to the accompanying drawings a solid piece of leather is shaped in the form of 15 an insole 1 as shown in perspective view in Fig. 1. The insole 1 is divided horizontally at the toe portion and at the shank and heel portion as indicated at 2 and 3 in Fig. 2 leaving a solid ball portion 4 between the divided toe portion and 20 shank and heel portion. Into the divided toe portion and shank and heel portion there is inserted a sheet 5 of thin vulcanite, vulcanized board or similar material. The three layers at the toe portion and shank and heel portion are 25 suitably dressed with an adhesive and pressed into a solid member as shown in Fig. 4. There is thus formed an insole which is formed of three 30 ply material at the toe portion and shank and heel portion with a solid ball portion 4.

An insole thus produced has the advantage of 35 being extremely thin and at the same time possessing a high degree of strength and solidity at the toe portion and shank and heel portion, thus preventing spreading and distortion of the shape 25 of the boots and shoes during manufacture and whilst being worn. At the same time flexibility is retained at the point at which flexibility is required, that is to say produces greater comfort whilst the boot or shoe is being worn.

The insole thus produced is then subjected to 40 a splitting or skiving process for the purpose of marginally reducing the thickness on its lower surface indicated at 6 in Fig. 5. This marginal reduction of thickness is effected for a distance 45 of $\frac{1}{2}$ " to $\frac{5}{8}$ " from each edge of the toe portion, known as the lasting margin, thereby leaving a central projecting portion 7. This projecting portion 7 subsequently serves to form the equivalent 50 of bottom filling materials which have hitherto usually been used at a later stage in the manufacture of boots and shoes. By the provision of the projecting portion 7 the use of bottom filling materials and the process of bottom filling 55 are thus dispensed with. The lasting margin

thus formed and also the ball portion of the insole is now coated with a layer of adhesive as indicated at 8 or there is fitted thereon a strip of fabric or other suitable material which is dressed on both sides with an adhesive preparation. The exposed adhesive is preferably covered with a layer of "CELLOPHANE," or other suitable material of which a portion is indicated as slightly raised at 9 in Fig. 6. This covering 9 is provided for the purpose of facilitating the handling and storing of the insoles as it prevents them from adhering to one another or to any undesired substance, but can be removed easily when required subsequently in the manufacture of the boots and shoes.

In Fig. 7 the shank and heel portion of the insole is reinforced by means of a metal shank stiffener 10. In the usual process of manufacture of boots and shoes the shank stiffener 10 is attached to the insole after the shoes are lasted during the process of bottom filling. When this is done a difficulty is generally met with in getting the shank stiffener close down to the insole as the lasting margin of the upper comes between the insole 1 and the shank stiffener 10.

Incorporating the shank stiffener 10 in the insole has the advantage of ensuring close contact and alignment with the insole and the retention of the exact contour for the shank and heel portions of the last to which the insole is to be applied.

For the purpose of rendering the projecting portion 7, which extends from the toe portion to the solid portion 4, more flexible it is provided with a series of transverse and intersecting incisions extending at different angles as indicated at 11 in Fig. 7.

The linings of uppers to be attached to an insole as above described are so designed as to leave approximately $\frac{3}{8}$ " to $\frac{1}{2}$ " of the flesh side of the upper extending beyond the lining at that part known as the lasting margin. Consequently the lining requires less material than hitherto whereby a saving in lining material is effected.

For the purpose of attaching an upper to an insole in accordance with the invention, the insole is attached to a last 12 (Fig. 8) in the usual way. After the insole has been fixed in position 50 the "Cellophane" or like covering 9 is removed so as to expose the adhesive layer 8 or the adhesive surface of the strip. An upper 13 is now pulled over by hand or by the usual machine method. For this purpose it is not necessary to use any tacks as in the case of the hand operation the upper is hammered on to the adhesive layer or the machine is fitted with a hammering device instead of tacking mechanism for this purpose.

60 The lining of the upper at the toe portion and ball portion only engages with the lasting margin of the insole for a distance of approximately $\frac{1}{8}$ " from the outer edge of the insole, whilst the lasting margin of the upper engages the complete width of the lasting strip or lasting margin 8 not covered by the lining. The uppers are first

fastened to the insole by hammer blows at points 14, 15 and 16 in Fig. 8. The toe portion of the upper is then completely lasted to the insole by hand or by the usual machine method as indicated at 17 in Fig. 9. Thereupon the fore part of the upper, generally referred to as the var is lasted to the insole by hand or by the usual machine method as indicated at 18. The shaft portion of the upper is also lasted to the insole as indicated at 19 by these methods.

As the upper is secured to the insole by adhesion there is no necessity for using tacks, nails or staple wire and the machines used for the purpose of applying the upper to the insole are fitted with a hammering device instead of a tacking mechanism.

The lasting of the heel portion 20 is also effected by hand or by means of a lasting machine in the usual way.

Fig. 10 shows a section of an upper which has been secured to an insole in accordance with the invention. The upper is indicated at 13 and the insole at 1. The skived margin of the insole is indicated at 21. The lining 22 of the upper is lasted over to a distance of approximately $\frac{1}{8}$ " as indicated at 23, whilst the graduation of the lasting margin of the uppers (that is to say outside materials and lining materials) is produced by causing the upper material to continue over the lasting margin 21 of the insole 1 to a point 24. This graduation of the upper corresponds with the graduation produced by skiving the lasting margin 21 of the insole 1 and when the upper has been secured to the insole the outer surfaces of the upper and the projection 7 are in alignment. As a result there is no cavity formed between the inner edges of the upper which would normally require filling with filling materials as this space is now filled up by the projecting portion 7 which is formed integral with the insole.

The outer soles can now be attached or fastened to the shoe in the usual way, that is to say either by sewing or by means of adhesive.

Having thus described my invention, what I claim as new therein, and desire to secure by Letters Patent, is:—

An insole for use in the manufacture of boots and shoes, comprising a solid ball portion, a toe portion formed integral with said ball portion, a shank and heel portion formed integral with said ball portion, said toe portion and said shank and heel portion being divided horizontally, sheeting inserted in the said divided toe and shank and heel portions, said insole being marginally reduced in thickness on its lower surface so as to form a projecting portion, said projecting portion being adapted to form the equivalent to bottom filling materials, said projecting portion having transverse and intersecting incisions extending at different angles formed therein, a metal shank stiffener secured to said insole longitudinally on the shank and heel portions, said metal shank stiffener serving to reinforce the shank and heel portions of said insole.

ERNEST ALBERT PARKER.
